UNITED STATES PATENT OFFICE

ROBERT H. INGERSOLL, OF NEW YORK, N. Y.; CHARLES S. SMITH, OF LANSING, MICHIGAN; AND FREDERIC C. LEUBUSCHER, OF ESSEX FELLS, NEW JERSEY, EXECUTORS OF SAID ROBERT H. INGERSOLL, DECEASED, ASSIGNORS TO ROBT. H. INGERSOLL, INC., OF NEW YORK, N. Y., A CORPORATION OF NEW YORK

RAZOR-BLADE STROPPER

Application filed September 24, 1925. Serial No. 58,371.

This invention relates to improvements in holders for razor blades for use during stropping of the blade.

One of the objects of the present invention is to provide a simple and cheaply constructed holder of this type. Another object is to provide a guard for the blade which is rigidly fastened to the holder proper, and which is resiliently capable of yielding during the stropping operation to permit the edge of the blade to be presented to the strop at the proper angle under the pressure employed during stropping, and which upon the cessation of such pressure is automatically and immediately returned to the original position. Another object is to provide a holder of this type which has few parts and in which these parts are secured together in a permanent manner so that parts thereof cannot be misplaced or lost. A further object is to provide a blade holder of this type in which the blade is easily and quickly inserted and secured within the holder, and the device as a whole may be operated by an unskilled or careless person without danger to the flesh or the strop.

With these and other objects in view, there are shown on the accompanying drawings several forms of the invention, in which:

Fig. 1 is a plan view of a first form of construction with the holder closed upon a blade.

Fig. 2 is a similar view, with the holder opened.

Fig. 3 is a section on line 3—3 of Fig. 1, on an enlarged scale.

Figs. 4 and 5 are sections on lines 4—4 and 5—5 respectively of Fig. 1, on an enlarged scale.

Fig. 6 is a fragmentary plan of a modified form of execution adapted to a single-edge blade.

Fig. 7 is a plan view of a further modification, in the closed position.

Fig. 8 is a section on line 8—8 of Fig. 7, on an enlarged scale.

Fig. 9 is a plan of a further modification, in the closed position.

Fig. 10 is a section on line 10—10 of Fig. 9, on an enlarged scale.

Fig. 11 is a section on line 11—11 of Fig. 9.

In Fig. 1, the blade holder is shown as having the two handle sections 10 and 11 which are pivoted together at one end by a hollow rivet 12. In form, each of these handle sections has at the pivot end an aperture to receive the pivoting rivet 12, and adjacent thereto a transverse ridge 13 of greater length than the normal width of the handle section and projecting at each side: which is cut away at 14 on the portions of these handle sections facing each other, as will be more fully described hereinafter. The handle sections then have slightly arched portions 10^a, 11^a of normal width adapted to receive and clamp a razor blade B between them followed by a second transverse ridge 15 of substantially the same length as that at 13 and likewise projecting to each side, and cut away at the meeting faces at 16. Each handle section blends gradually from this ridge to form the handle portions proper, which when secured together form the hollow handle of appropriate thickness to enable the user to obtain a good grip upon the device.

These handle sections, in Fig. 1, are held together and upon the razor blade B by a cup 19 which is adapted in size to fit tightly over the two hollow sections 10 and 11 at the end removed from the pivot point. This cup 19 is carried by a slider 20 which is fastened securely to the handle section 11 by a rivet 21 with a large head, which passes through a slot 22 in the slider. The slider may be moved back and forth upon this rivet, and is guided in invariable lateral relation to the handle sections by the projecting sides of the handle section 11.

The guard for the edges of the razor blade consists of the two longitudinal elements 23, 24, which are gashed or slit at their ends to receive thin sheets 25, 26 of spring metal such as brass, and united therewith by soldering or the like to produce a rigid connection. These sheets 25, 26 are each made T-shaped in plan, and are secured at the stem of the T to the handle section 11, as shown in Figs. 2 and 3, by passing the stem of sheet 25 beneath the handle sections 10 and 11 in assembling the device, and by employing the rivet 27 for the sheet 26. Since the sheets 25, 26

are connected together by the elements 23, 24, and the rivets 12 and 27 are drawn tight, the guard assembly is held rigidly and substantially immovably at its central section in the handle section 11. The razor blade B is received between the sheets 25, 26 as indicated in Figs. 2 and 3. The transverse bars of the T-shaped sheets are held therefore in rigid alinement with and between the transverse ridges 13 and 15 of the handle sections 10 and 11, but by the resiliency of their material are permitted to rock under the pressure of stropping into a position such as shown in dotted lines in Fig. 4, in which the element 23 or 24 which has been rocked uncovers the edge of the blade and permits the latter to present itself to the strop at the proper angle.

The blade B is received between the two sheets 25, 25, as shown in Figs. 2 and 3, and is preferably held against displacement either longitudinally or transversely of the handle sections by the lugs 30 which are made solid with the portion 11^a of the handle section 11, and pass through the usual apertures in the central line of the double-edge type of blade, and thereby secure the blade against displacement.

In operation, with the blade holder in the open position as shown in Fig. 2, a razor blade B is placed loosely in the holder, with the lugs 30 passing through its apertures. The handle section 10 is then rotated about the pivot 12 until it lies parallel to and against the handle section 11. The cup 19 is then pushed inward to bind the two handle sections together. The handle sections are preferably formed so that they spring apart slightly, and this resiliency is employed to hold the cup 19 in place upon them.

The holder and blade are then ready for use. The user grips the holder and strop and rotates the holder slightly and pushes one of the guard elements downward against the strop while holding the holder in a somewhat oblique position, at the same time moving the holder along the strop in the customary manner. The guard element rocks away by reason of the resiliency of the sheets 25, 26 and permits the edge of the blade B to be presented to the strop at the predetermined and proper angle established by the angle of the cut-away portions 14, 16.

When the stropping is completed, the cup 19 is pulled out, the handle sections 10 and 11 spring apart, and the handle section 10 may be rotated about the pivot 12 to the position shown in Fig. 2, and the blade lies free for removal.

In the modified form shown in Fig. 6, the holder is adapted for a single edge blade having a thickened back. The construction in general is the same as with the previous form except that the ridges 14^a, 16^a project at one side only. The thickened back of the

blade is received and clamped by the slightly arched construction shape of the handle sections 40 and 41 which resemble the handle sections 10^a and 11^a, to prevent transverse movement of the blade in the holder, except that the lugs 42 are provided at the ends of the position of the blade to prevent the blade from moving longitudinally of the holder. Pivot 43 connects the handle sections 40, 41. The operation is the same as before.

In the modified form shown in Figs. 7 and 8, the two handle sections 50 and 51 are connected by a transverse pivot, formed by curling the end 52 of section 50 and passing it through an aperture 52^a of section 51. The arrangement of the ridges 14^b, 16^b and of the guard is the same as before except that an individual rivet 27^b is also provided for the sheet 55 as well as the rivet 27^c, sheet 56. The handle sections 50, 51 in this case are held together by a slider 54 which is mounted for movement relative to the handle section 51 by a rivet 53 which passes through a slot 57 in the handle section 51 and has an enlarged head 58 which holds the slider in fixed sliding relation with the section 51: the upwardly curled side portions of the handle section 51 guide the slider 54 in its movement. A further lug 59 with an enlarged head 60 is adapted to pass through the enlarged end 61 of a slot 62 formed in the handle section 50 and thereafter to be forced with the slider 54 into the narrower end of this slot, to hold the handle sections tightly together: the two members 58 and 60 are easily accessible for the fingers of the user, and enable him to manipulate the device with great facility. The construction and operation are otherwise the same as with the form of Fig. 1.

In the modified form of Figs. 9 and 10, the portions of the handle sections for clamping the blade, and the guard are the same as with Figs. 7 and 8; but the securing arrangement for the handle sections 70 and 71 comprises a sleeve 72 which slides over the two handle sections. The section 71 is much longer than the section 70, and is rebent at its end, so that the rebent portion 71^a lies parallel to the outwardly extending portion and forms therewith a hollow tube, which extends inward to the end of the handle section 70. The portion 71^a has a longitudinal slot 73 therein, to receive a lug 74 fixed in the sleeve 72, as shown in Fig. 11: the length of this slot is sufficient to permit the sleeve 72 to be withdrawn from over the handle section 70, which may then be swung upwardly and away about its pivot as shown by the arrow 76. The operation and construction are otherwise the same as before.

It will be noted that in all of these devices, the handle sections, guard, and handle section securing means are rigidly and permanently fastened together. In all of them the

guard is rigidly fastened at its central longitudinal line to one of the handle sections, but it is permitted to yield resiliently by the manner of its mounting; and is limited in this movement at each end of the razor blade by 5 the cut-away portions of the transverse ridges.

Other modifications may be made in the form and arrangement of the parts within the scope of the appended claims.

10 I claim:

1. In a blade holder for razor blades for use during stropping, a pair of handle sections having blade clamping portions and transversely extending stop portions thereon cut away to expose the guard to permit a limited lateral play therewith, releasable means to secure said handle sections together, and a solidly united resiliently supported guard connected to one of said handle sections and 20 adapted to be limited in its resilient movement by said stop portions of said handle sections.

2. In a blade holder for razor blades for use during stropping, a pair of handle sections 25 having blade clamping portions and transversely extending stop portions cut away to expose the guard to permit a limited lateral play therewith, means carried by one of said handle sections to secure the other releasably thereto, and a guard rigidly connected to one of said handle sections and having a resiliently supported bar arranged parallel to an edge of the blade and limited in its movement 30 by said stop portions.

3. In a blade holder for razor blades for use during stropping, a pair of mutually pivoted handle sections having integral razor blade clamping means thereon, and a resilient guard rigidly fastened to one of said handle members to protect the edge of a razor blade mounted in said handle sections, and adapted to resiliently yield to expose the blade to a strop, said handle sections cut away to expose the guard to permit a limited lateral play therewith while limiting the movement 45 of said guard in such movement.

4. In a blade holder for razor blades for use during stropping, a handle, blade-receiving and holding devices secured to said handle and having stops thereon cut away to expose the guard to permit a limited lateral play therewith, a guard, and means connected to said devices to support said guard opposite the edge of the razor blade in said devices, 55 said means including a resilient arm located between said stops and limited in its resilient movement thereby.

5. In a blade holder for razor blades for use during stropping, a handle, blade receiving and holding devices secured to said handle, opposed stops on said handle, a guard, and a resilient member located between the stops and connected to said holder and guard 60 to support said guard opposite the edge of

the razor blade held in said devices, said member being limited in its movements by said stops.

In testimony whereof, I affix my signature.

ROBERT H. INGERSOLL.
